Primary Examiner — Susan E Krakower(74) *Attorney, Agent, or Firm* — Dorsey & Whitney LLP**CLAIM**

The ornamental design for an exercise bike flywheel housing, as shown and described.

DESCRIPTION

FIG. 1 shows a front perspective view of an exercise bike flywheel housing;

FIG. 2 shows a front elevation view of the flywheel housing of FIG. 1;

FIG. 3 shows a rear elevation view of the flywheel housing of FIG. 1;

FIG. 4 shows a left elevation view of the flywheel housing of FIG. 1;

FIG. 5 shows a right elevation view of the flywheel housing of FIG. 1;

FIG. 6 shows a top view of the flywheel housing of FIG. 1; and,

FIG. 7 shows a bottom view of the flywheel housing of FIG. 1.

The broken lines illustrate environmental structure and form no part of the claimed design.
